DAVID T. WILLIAMS, OF PATERSON, NEW JERSEY, ASSIGNOR TO STANDARD STOKER COMPANY, INC., OF WILMINGTON, DELAWARE, A CORPORATION OF DELAWARE.

AUTOMATIC STOKING MECHANISM.

1,152,682.

Specification of Letters Patent. Patented Sept. 7, 1915.

Application filed December 6, 1913. Serial No. 805,021.

To all whom it may concern:

Be it known that I, DAVID T. WILLIAMS, a subject of the King of England, residing at Paterson, in the county of Passaic and 5 State of New Jersey, have invented certain new and useful Improvements in Automatic Stoking Mechanisms, of which the following is a specification.

This invention relates to automatic stoking mechanisms and the like and its object 10 is to provide an arrangement of elements whereby to accomplish the simultaneous advance of the fuel and the reducing by pressure of lumps or pieces thereof to or below 15 a given size.

The invention consists in providing, beside a definite course in which the fuel is advanced by means having a fuel-pushing abutment operating in said course to exert 20 reducing pressure on the fuel, means against which reducing pressure is exerted by said abutment while the fuel is being advanced in said course, the second-named means having a roughened fuel-abutment surface facing 25 oppositely to the direction of advance of the fuel.

The invention consists, further, in providing the bunker of a locomotive tender with a forward fuel-support including an upper 30 movable portion and a lower rigid portion and associating therewith means to advance the fuel in a forward course under the support having a fuel-pushing abutment, the fixed portion of the support affording means 35 against which fuel-reducing pressure is exerted by said abutment while the fuel is being advanced.

The invention still further consists in providing, with a fuel supporting trough and 40 a rotary screw extending longitudinally of and arranged in said trough, an abutment plate coactive with the screw to exert reducing pressure on the fuel, the same having a recess receiving, and the margin of said 45 recess close to, said screw and also having its fuel-abutment surface extending in a plane substantially perpendicular to the axis of the screw.

In the accompanying drawings, wherein

the invention is fully illustrated, Figure 1 50 illustrates the invention in its preferred form applied to a locomotive tender, the parts appearing in longitudinal vertical substantially central section; Fig. 2 is a transverse vertical sectional view on line $x-x$ of 55 Fig. 1; and, Fig. 3 is a vertical sectional view of said second-named abutment.

The locomotive tender a ; its coal bunker or bin b having its bottom formed in part by the forwardly inclined wall c and in 60 part by the walls d inclined from the sides of the tender body toward the central vertical plane thereof, where they meet the upper edges of a centrally located, longitudinally arranged, semi-circular trough e 65 forming a part of the means whereby the coal is advanced from the bunker and fed to the fire-box of the locomotive; the screw f journaled in said trough in suitable bearings g ; the forward deck or platform h 70 formed with an opening i over the screw and provided with a removable cover j for said opening; and the hinged doors k arranged at the back of the deck and forming a forward support for the coal when the 75 bunker is full, the same extending short of the screw to afford access to the coal for hand-firing are or may be all substantially the same as in the improvements in automatic stokers set forth in my application 80 Serial Number 802,906.

l designates planking removably arranged in suitable guides and adapted normally to support the body of coal at the opening under the doors k . One of the bulkheads m 85 in the water-space n of the tender forms a fixed front wall for the lower part of the bunker, being cut out centrally from its upper edge downwardly to receive the trough e . To this bulkhead, in the preferred construction, I secure the aforementioned fuel-abutment. Referring to the drawings, and particularly Fig. 3, this consists of a stout metal plate o having a curvilinear opening p formed in its lower edge and provided 90 on one side thereof with the spurs or sharp lugs q . This plate is bolted flatwise against the bulkhead m with its spurs or lugs pro-

jecting rearwardly and so that the screw is received in its opening, as shown in Fig. 2. It is arranged relatively close to the screw, and to render it adjustable to and 5 from the screw it is provided with vertical slots *r* through which the bolts *s* for securing it to the bulkhead pass.

When the stoking mechanism is in operation those fragments of the fuel that are 10 already properly reduced in size are carried forward by the screw in the trough in the usual manner, unaffected by the fuel-abutment *o*. The large lumps, however, work toward the front of the bunker where they 15 bank up against the removable planking *l* and the abutment (which in the present case forms with the planking the forward fuel-support of the bunker.) In the rotary movement of the screw they are in one way or another, according to their size and state of hardness 20 and other conditions, reduced in size by the coaction of the blades or abutments *f'* of the screw *f*, as they act to push them forward, and the fuel-abutment *o*. The spurs *q* serve partly to split or cleave the lumps and 25 partly to keep them in position to be crushed when once they have come within the coacting crushing influence of the screw and abutment *o*. If a lump is too large at once to be reduced to fragments that will pass under the abutment *o* the crushing resolves itself 30 into a grinding away of the lump until it is sufficiently small so that it will be reduced at a single operation.

35 Realizing the value of reducing the larger lumps of coal to a size that can be handled successfully in automatic stoking, thereby rendering it unnecessary to specially prepare the coal previously to supplying it to 40 locomotives, previous inventors have suggested various means, adjunctive to the stoking mechanism, for converting the coal to a uniformly suitable size. These have generally proven unsuitable either because, if 45 self-contained and separate from the stoking mechanism, they involved extra first cost and additional expense for upkeep, or because, if a part of the stoking equipment, they did not effectually accomplish the de- 50 sired object, but were liable frequently to jam because incapable of disposing of certain lumps that were either too large or too hard to respond to the crushing or breaking action. Considerable practical use of my 55 invention has demonstrated that, without special equipment of any kind other than the abutment *o* or its equivalent, "run of mine" coal (to wit, coal as it comes from the mine, unprepared) may be handled without 60 any interruption of the operation of the mechanism, this being obviously due to the fact that the elements directly concerned in the disrupting of the coal lumps attack each

lump with the exercise of exceedingly great force applied so that not the whole, but only 65 a part of the lump, offers resistance.

I do not wish to be limited to the precise construction herein shown and described,

What I claim being—

1. A fuel conveying mechanism for automatic stokers including means to advance the fuel in a definite course having a fuel pushing abutment operating in said course to exert reducing pressure on the fuel and means beside said course against which reducing pressure is exerted by said abutment while the fuel is being advanced in said course, the second-named means having a roughened fuel-abutment surface facing oppositely to the direction of advance of the fuel. 75

2. A fuel conveying mechanism for automatic stokers including a fuel-supporting means over which to advance the fuel in a definite course, means to advance the fuel in said course having a fuel-pushing abutment operating in said course to exert reducing pressure on the fuel, and means beside said course against which reducing pressure is exerted on the fuel by said abutment while 85 the fuel is being advanced, the last-named means having a roughened fuel-abutment surface facing oppositely to the direction of advance of the fuel. 90

3. A fuel conveying mechanism for automatic stokers including means to advance the fuel in a definite course having a fuel-pushing abutment operating in said course to exert reducing pressure on the fuel and a plate arranged beside and in a plane transverse to said course and against which reducing pressure is exerted by said abutment on the fuel while the latter is being advanced in said course, said plate having the surface thereof facing oppositely to the direction of advance of the fuel roughened. 95 100

4. A fuel conveying mechanism for automatic stokers including means to advance the fuel in a definite course having a fuel-pushing abutment operating in said course 110 to exert reducing pressure on the fuel and a plate arranged beside and in a plane transverse to said course and against which reducing pressure is exerted by said abutment on the fuel while the latter is being advanced 115 in said course, said plate having the surface thereof facing oppositely to the direction of advance of the fuel provided with spurs. 120

5. In combination, a fuel bunker, said bunker having a forward support for the fuel including an upper movable and a lower rigid portion, and means to advance the fuel in a forward course under said support having a fuel-pushing abutment, the lower rigid portion of said support affording 125 means against which fuel-reducing pressure

is exerted on the fuel by said abutment while the fuel is being advanced.

6. In combination, a fuel supporting trough, a rotary screw extending longitudinally of and arranged in said trough, and an abutment plate coactive with the screw to exert reducing pressure on the fuel said plate having a recess receiving, and the margin of said recess close to, said screw and

also having its fuel abutment surface extending in a plane substantially perpendicular to the axis of the screw.

In testimony whereof I affix my signature in presence of two witnesses.

DAVID T. WILLIAMS.
